UNITED STATES PATENT OFFICE

2,193,499

CONDENSER ATTACHMENT

William B. Towell, Port Arthur, Tex.

Application August 6, 1937, Serial No. 157,703

1 Claim. (Cl. 138—97)

This invention relates to condensers and particularly apparatus of this kind used upon ships or vessels, through which salt water from a circulating bottom is passed and utilized as a cooling agent for the condenser, and particularly to an attachment to condensers of this kind for providing a temporary repair in the event of a leak in one or more condenser tubes to stop such leak until such time as the required repair can be made thereon; and the object of the invention is to provide an attachment in the form of a hopper-shaped container in which sawdust, ground cork, or other similar light particles may be placed, means for discharging such particles from the hopper into the circulating system of the condenser whereby such light particles will be picked up or drawn into a hole, crack, or crevice, of one or more tubes of the condenser by the vacuum prevailing therein, and to form what may be termed calking, plugging, or sealing elements to close such holes, crevices or cracks to form a temporary seal in the condenser preventing further leakage of the salt water into the condenser and eliminating the damage caused by the admission of water into the condensed feed water of a boiler as will be apparent; a further object being to utilize the circulating water coming under pressure from the sanitary line or other source of supply as a means for injecting under pressure the particles into the water circulated through the condenser; a further object being to provide an attachment having at the lower end of the hopper thereof a nozzle discharge for said water with means for by-passing part of the water to the upper end of the hopper to encourage the discharge of the particles therefrom, and to the provision of valves controlling the supply of water to said attachment and the discharge of the water and particles therefrom, and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic sectional view through a condenser showing one of my improved attachments coupled therewith, and

Fig. 2 is a view similar to Fig. 1 showing only

the attachment on an enlarged scale and with parts of the construction in section.

It is necessary in ocean-going steamships to collect all spent steam, condense the same and use the condensate as the chief supply of boiler feed water. The cooling water for the condensers employed is taken from the sea and returned thereto after being used. In the past, leaks in the internal walls of the condensers allowing sea water to enter the feed water have necessitated either stopping the vessel to repair the leaks, or running to port allowing the salt water to continually accumulate in the feed water. Either of these procedures is expensive because of time lost and damage done to the equipment. It is the purpose of my invention to eliminate this expense by effecting a temporary stoppage of leaks developing at sea.

To illustrate one use of my invention, I have shown in Fig. 1 of the drawing a condenser comprising an outer casing 6 having removable end plates 7 and 8. In the upper portion of the outer casing 6 is a steam inlet 9 and in the lower portion thereof a condensate outlet 10. Within the condenser 5 and between the outer casing 6 and the end plates 7 and 8 are spaced plates 11 supporting horizontal tubes 12, 12a. The chamber 13 enclosed between the casing 6, the spaced plates 11 and the tubes 12 and 12a, is under a high vacuum when the condenser is operating.

End plate 7 is divided by baffle-plate 14 into upper chamber 15 and lower chamber 16; and end plate 8 forms a continuous chamber 17. The circulating cooling water of the condenser enters chamber 16 through inlet 18, passes through tubes 12 to chamber 17 and from there through tubes 12a to chamber 15; and is exhausted through outlet 19.

In the lower portion of end plate 7 and near the inlet 18 is an opening 20 connecting with a pipe 21 in which is mounted my attachment 22.

In Fig. 2 of the drawing, I have shown my attachment as comprising a container 23, a hopper discharge 24 in the lower portion thereof integrally joining at opening 25 a cylindrical cross-head 26 having coupling ends 27 and 28 and a cylindrical chamber 29. Inserted through end 28 of said crosshead is a pipe 30 having a nozzle 31 extending under the opening 25. A gland 32 is employed to pack or seal the pipe 30 in the end 28. The outwardly extending end 33 of pipe 30 is connected through a cross-connection 34 to a pressure water supply pipe 21a having means for closing off the water supply as shown by gate valve 35. Also joining the cross-connection 34 is an

upwardly extending pipe 36 coupled with the container 23 of the device at opening 37 in the upper portion thereof, said pipe having union coupling 36a to facilitate assembling of the attachment. 5 Extending downwardly from the cross connection 34 is a drain pipe 41 having means as shown by valve 42 for closing off said pipe as seen in Fig. 1 of the drawing.

End 27 of the cylindrical crosshead 26 joins 10 the condenser end 7 at opening 28 through pipe 21 having means as shown by gate valve 38 for closing off said pipe. The upper end of the container 23 of the device has a removable cover 39 with means as shown by the threaded section 40 15 for obtaining a tight seal.

The purpose of my device is to provide for the temporary sealing of small leaks in the tube or plate surfaces which allow circulating water to enter chamber 13. In reaching this end, I put 20 a charge of light granular inert material such as sawdust in the container 23 and securely close the cover 39. Valve 38 is then opened to the circulating water of the condenser and valve 35 to a source of water under pressure such as the sanitary line of the vessel. This water under pressure enters cross-connection 34 and is divided 25 into two streams, one passing through pipe 36 into the upper section of container 23 and carrying the granular material downward therein. 30 The other stream passes through pipe 38 and nozzle 34 becoming a high velocity jet in chamber 29. This high velocity jet operates as an injector picking up the granular particles at opening 25 and carrying them through pipe 21 into chamber 35 13, there to thoroughly mix with the circulating water. The particles are then carried through the tubes by the circulating water contacting the internal surfaces of the tubes and the surfaces of the plates. When the particles pass over the 40 area of the leak, some of them are drawn into the hole or crack of the leak by the vacuum in chamber 13 outside the tubes, thereby plugging or calking the hole and stopping the leak. When the stoppage is effected the attachment is shut 45 off by closing valves 35 and 38. If necessary, this procedure can be repeated at intervals until such time as permanent repairs can be made. When the attachment is shut off by closing valves 35 and 38 the pressure in the attachment may be 50 released or the attachment drained by opening the valve 42.

Periodic tests of the boiler feed water would indicate the presence of impurities caused by a leak in the condenser; and the great value of my device in practice is that it provides the immediate stoppage of such leak and effects a tem- 55

porary repair which will permit the vessel to proceed to port without loss of time. The checking of the leak prevents further pollution of the boiler feed water and the small amount of impurity that entered before the discovery of the leak can be neutralized by chemical treatment so that it will not cause appreciable damage to the boilers. 5

It should be borne in mind that my invention is not limited to the specific details of the construction shown, which construction is merely a form that I have found successful in operation. The chamber of the device can be kept filled and ready to use at all times but the device remains inoperative as long as the valves are closed; and 15 the granular material used is not necessarily limited to sawdust, but may be any other light granular inert material such as ground cork, grain, and the like.

It should be further borne in mind that my 20 attachment is not limited to use in connection with condensers or to the injection of plugging particles into pressure equipment, but may have other applications where it is necessary to discharge quantities of granular material by a pressure means from a storage chamber therefor.

Having fully described my invention, what I claim as new and desire to secure by Letters Patent, is:

An emergency repair attachment for injecting 30 particles of light inert calking material into the circulating water of a condenser of the class described, said attachment comprising a large casing having a discharge at one end opening into an elongated transverse tube at said end of the 35 casing, the other, upper end of the casing being open, a detachable closure cap for the open end of the casing to form a closed chamber therein, a nozzle supported in said transverse tube with the discharge end of the nozzle adjacent the discharge 40 of said casing, a valve controlling the discharge from said tube into a condenser in connection with which the attachment is coupled, means for passing water, under sufficient pressure to enter the circulating water of the condenser, through said nozzle for feeding inert particles from the casing into the circulating water of the condenser to effect a temporary repair of a leak which may prevail in the tubes of the condenser, a valve controlling said last named means, 45 and means between said last mentioned valve and the nozzle for placing the water under pressure in direct communication with the upper end of the casing to aid in the discharge of inert particles from said casing. 50
